MATCH BOX

William I. Kreisner, 145 Concord Ave., Oceanside, N.Y.

Filed Apr. 26, 1961, Ser. No. 64,912

Term of patent 14 years

(Cl. D48—29)

FIG. 1

FIG. 2

FIG. 3

FIG. 1 is a perspective view of a match box, showing my new design;

FIG. 2 is a bottom perspective view thereof as seen from the opposite side and end of FIG. 1; and

FIGS. 3 and 4 are enlarged fragmentary cross-sectional views taken along lines IIII—III and IV—IV of FIGS. 2 and 1, respectively.

The dominant features of my design reside in the portions shown in full lines.

The lining on the drawing represents contrastingly colored areas.

This application is a continuation-in-part of my co-pending application Ser. No. D 62,731, filed November 4, 1960 and now abandoned.

I claim:

The ornamental design for a match box, as shown and described.
